UNITED STATES PATENT OFFICE.

CARL FRIEDRICH NEBENDAHL, OF WANDSBECK, GERMANY.

AUTOMATIC IGNITING DEVICE FOR GAS-LAMPS, &c.

SPECIFICATION forming part of Letters Patent No. 604,074, dated May 17, 1898.

Application filed August 31, 1897. Serial No. 650,191. (No model.)

To all whom it may concern:

Be it known that I, CARL FRIEDRICH NEBENDAHL, a subject of the German Emperor, and a resident of Wandsbeck, near Hamburg, in the Province of Schleswig-Holstein, Kingdom of Prussia, German Empire, have invented certain new and useful Improvements in Automatic Igniting Devices for Gas Lamps or Lanterns, of which the following is a specification.

The present invention is an automatic igniting device for gas-lanterns, to be actuated by a float which sets the lamp in and out of action as soon as the pressure of the gas decreases from the main increases or decreases by having a pendulum or bell-crank valve acted upon in such a manner that it closes off the channel of the igniting-tube when the pressure of the gas is increased after having opened the feeding-channel of the lighting-flame and after the latter has been ignited by the igniting-flame, and that it (the bell-crank valve) closes off the feeding-channel of the lighting-flame whenever the pressure of the gas is reduced, after having opened the igniting-channel and produced the igniting-flame. It is presumed for this invention that the difference in the height of pressure amounts at least to five millimeters. The admission of higher differences of pressure is unlimited, and in such cases a reduction during the operation of the lamp is of no consequence. The operation of the new apparatus remains the same at all degrees of pressure. The apparatus is adjusted by the weight of the float in such manner that the lighting-flame disappears and the igniting-flame appears during the day-pressure of the gas. The equivalent of one millimeter gas-pressure is two grams. If, for instance, it is intended to extinguish at a certain time at a day-pressure of twenty millimeters a certain number of lamps and to have another certain number of lamps left burning, the weight on the floating body of the igniting device will have to be increased to the extent of ten grams and the pressure must increase at least from twenty to thirty millimeters. It is obvious that these lamps will only start burning after the pressure has risen to thirty millimeters

and that they will become extinguished if the pressure decreases to twenty-five millimeters. A greater difference in the pressure insures the igniting device being more reliable and indifferent to and not affected by variation of pressure, vibration, or shaking.

The invention, by way of illustration, is shown in the annexed drawings in one of the forms most suited for practical use.

Figure 1 is a vertical section through an automatic igniting device arranged according to the invention. Fig. 2 is a section on line 1 of Fig. 1. Fig. 3 is a plan illustrating the connection of the floating bell with the lever-valve.

A tube *b* branches off from the tube *a*, the latter leading to the burner *B* and to the lighting-flame, respectively, which (*b*) ends with a tube *b'* in a casing *c*, filled with glycerin or other liquid. A floating bell *d* is arranged in the casing *c*, the weight of which is reduced as far as necessary by virtue of a cork ring *d'* or the like, which helps to buoy it up. The floating bell which is immersed in the liquid is so arranged over the tube *b'* that the gas therefrom will lift the floating bell more or less, according to the pressure of the gas.

The floating body *d* is connected to the spindle *f* of the lever-valve *g*, which is arranged in the chamber *a'*, by means of a rod *e*, rail, or the like, whereby the parts *e f g* form a bell-crank. The chamber *a'* is connected to the gas-feeding tube *a* by means of the tube *a'*. Adjustable channels *h* and *i*, which are screwed to the chamber-jacket or adjustably arranged in any other suitable manner, lead to the burner-tube *B* and to the igniting-tube or igniting-channel *Z*, respectively.

If the floating bell falls, the lever *g* presses against the channel *h*; but if the floating bell rises the lever *g* presses against the channel *i* in order to shut off in both cases the feeding of gas to the burner-tube *B* and the igniting-channel *Z*, respectively. The lift or rise of the bell is therefore limited by the lever *g*, the turn of the latter being determined and regulated by the adjustment of the channel *h* and *i*. The gas-tight connection between the lever *g* and the channels *h* and *i* is obtained by a packing substance arranged in the le-

ver—for instance, lead g' —against which the channels h and i are pressed to prevent an escape of gas, which would cause the lamp to be ignited.

5 In cases of removed counter-pressure—*i. e.*, when the immersion of the floating bell d does not correspond to the pressure—a suitable valve b^2 is arranged upon the tube b' , the body b^4 of which would shut off the gas-out-
10 let b^5 automatically in such cases. A suitable protection-cap c' forms the lid on top of the casing c for the floating bell. k are small weights placed around a spindle d^2 of the floating bell d in order to govern the weight
15 of the bell, according to the gas-pressure.

To render the lighting-flame indifferent to and unaffected by variation in pressure and vibration and to enable the apparatus to turn the lever-seat even in very small differences
20 of pressure, the pressure-conduit leading to the floating body, which actuates the shutting-off-valve device, is separated from the conduit leading to the flame, and energy and movement are suitably adjusted by means of
25 a bell-crank, according to the requirements and the dimensions of the lamp.

Supposing the floating bell has been weighted for a certain pressure, the shut-off cocks a^3 and b^3 being opened and the bell-
30 crank valve $e f g$ being in the position shown in Fig. 1, then the channel h , feeding the flame, will be closed. Consequently the gas is flowing through the opened channel i and the igniting-tube Z to the igniting-flame. The
35 igniting-tube having been once lighted, if it is desired to ignite the lamp it will only be necessary to increase the pressure of the gas. The floating bell will be lifted because of the increased pressure, and the bell-crank valve
40 will shut off the channel i after it has opened the channel h , leading to the lighting-flame, and after this latter has been ignited by the igniting-flame. When the gas-pressure is again reduced, the floating bell d and the
45 crank-valve go back into the position illustrated in Fig. 1, whereby the feeding-channel h for the lighting-flame will be shut off after the igniting-channel has been opened and after the igniting-flame has been ignited.
50 The lamp is then again extinguished and only the igniting-flame will be burning.

Having now particularly described and ascertained the nature of my said invention and in what manner the same is to be performed, I declare that what I claim is—

55 1. A gas-supply conduit, main and igniter burner passages communicating therewith through its vertical walls at diametrically opposite points, and a valve adapted to be moved by variations of the pressure in said conduit to close or open one of said passages and open or close the other, for the purpose set forth.

60 2. A gas-supply conduit, main and igniter burner passages communicating therewith through its vertical walls at diametrically op-

posite points, and a loaded valve adapted to be moved by variations of the pressure in the conduit to close or open one of said passages and open or close the other, for the purpose set forth. 70

3. A gas-supply conduit, main and igniter burner passages communicating therewith through its vertical walls at diametrically opposite points, a rocking valve adapted to be moved by variations of the pressure in said conduit to close or open one of said passages and open or close the other, and means for adjusting the amplitude of the rocking movements of said valve, for the purpose set forth. 75 80

4. A gas-supply conduit, main and igniter burner passages communicating therewith through its vertical walls at diametrically opposite points, a rock-lever carrying a two-faced valve at its free end, and appliances 85 adapted to be controlled by variations of the pressure in the conduit and thereby rock the valve-lever and move its valve to close or open one of said passages and open or close the other, for the purpose set forth. 90

5. A gas-supply conduit, main and igniter burner passages communicating therewith through its vertical walls at diametrically opposite points, a valve, and appliances outside of the conduit connected with said valve and controlled by variations of the pressure in the conduit and thereby move the valve to close or open one of said passages and open or close the other, for the purpose set forth. 95

6. The combination with a gas-supply conduit, main and igniter burner passages communicating therewith through its vertical walls, and a valve-lever carrying a two-faced valve at its free end, of a gas-holder, its bell in communication with said conduit and a connection between said bell and the valve-lever, whereby the latter is rocked by variations of the pressure in the conduit to close or open one of the aforesaid passages and open or close the other, for the purpose set forth. 100 110

7. The combination with a gas-supply conduit, main and igniter burners in communication therewith through its vertical walls at diametrically opposite points, and a rock-lever carrying a valve at its free end adapted to close or open one of said passages and open or close the other; of a gas-holder, its bell in communication with said supply-conduit, a connection between the bell and rock-lever whereby the latter is operated by variations 115 of the pressure in the conduit, and a pressure-controlled valve adapted to control the flow of gas to the bell, for the purpose set forth.

8. A gas-supply pipe, main and igniter burner passages leading therefrom, a valve-seat for each of said passages adjustable reciprocally, and a valve adapted to move from one seat to the other to open or close one of said passages and close or open the other, for the purpose set forth. 125

65 9. A gas-supply pipe, main and igniter burner passages leading therefrom, a valve-

seat for each of said passages adjustable reciprocallly, and a valve adapted to move from one seat to the other to open or close one of said passages and close or open the other, 5 said valve moved by variations of the pressure in the supply-pipe, for the purpose set forth. In testimony that I claim the foregoing as

my invention I have signed my name, in presence of two witnesses, this 19th day of August, 1897.
